UNITED STATES PATENT OFFICE

LUCIEN BÉGIN, OF PARIS, FRANCE, ASSIGNOR OF ONE-HALF TO WILLIAM B. WEAVER,
OF BIRMINGHAM, ALABAMA, AND HAROLD F. WILHELM, OF NEW YORK

ELECTRON DISCHARGE DEVICE

Application filed March 2, 1926, Serial No. 91,670, and in France March 14, 1925.

The present invention relates to a new method of supplying current to the electrodes of hermetic tubes and more particularly to the cathodes of high-power thermionic tubes. It is known that the construction of high power tubes of the order of 50 kilowatts or more involves, in addition to the use of special coating of the cathodes with a view of increasing their electron emitting power, the use of cathodes of large area and operating at high temperature which implies an appreciable power expenditure for the heating of said cathodes. As a general rule, the heating is effected electrically and, mainly for constructional reasons, at relatively low voltages. Now, whenever it is desired to lead in large currents through the walls of a vacuum tube, it is necessary to use lead-in conductors of such dimensions that the sealing of same through the tube walls offers great difficulties in maintaining the tube in a hermetic condition owing to the uneven expansion of the lead-in conductors and of the insulating material of the tube envelope. In accordance with the invention, the seals heretofore used may be partly or entirely suppressed and the insulating walls of the tube envelope used as the dielectric of two condensers hooked up in series internally through the cathode or other body which it is desired to bring to incandescence.

In the drawing:

Fig. 1 represents a three-element electron discharge device according to the invention whose cathode heating current is supplied thru condensers which utilize the envelope as their dielectric, the device having cooling means for controlling the operating temperature.

Fig. 2 illustrates a hook-up which may be used with an electron discharge device of the type shown in Fig. 1 according to the invention.

Fig. 3 illustrates another manner in which an electron discharge device may be constructed according to the invention, and

Fig. 4 illustrates an electron discharge device having a hook-up for supplying the cathode with both alternating and direct heating current.

Referring now to Figure 1, V designates the envelope having a middle branch and two side branches, the latter having preferably larger dimensions than the former in order to realize sufficient area of dielectric for the efficient transfer of the required power at suitable voltage and frequency as well as for the proper dissipation of the power expended through joulean effect and dielectric hysteresis. The inside walls of the side branches are coated with conductive coatings A_i , A_i , and the outside surfaces thereof are also covered by similar coatings A_e , A_e , having connections at F_a , F_a . The inside coatings A_i , A_i , are connected together through the cathode intended to absorb the power transmitted through the tube dielectric. The anode and grid are respectively connected to terminals P, G, and a suitable point of the cathode, intended to complete the path of the direct current resulting from the transfer of negative charges from cathode to anode, is connected to a third terminal F_c .

The power expended within the tube may be dissipated by causing the three branches of the tube to be immersed in refrigerating tanks H, H, H, in accordance with a known process.

The dynamic stresses exerted between the coatings A_i , A_e , through electrostatic attraction, will be far less than those which occur in known electromagnetic inductive heating methods comprising inside and outside coils, and it will only be necessary that the coatings be uniformly adherent to the walls of the vessel.

The form shown in Figure 1 is quite schematic and it will be possible to adopt any other shape whatever susceptible of fulfilling the conditions above described, exercising due care, however, to avoid shaping the vessel such as it would become fragile and difficult to handle or ship.

From the point of view of the losses occurring in the dielectric, it will be advisable to make use of a substance which, whilst possessing a high specific inductive power, will be as little conductive as possible and capable of withstanding high temperatures, such as quartz, pyrex glass or mere silica containing

a slight proportion of uranium. For that matter, it is not necessary to carry out the whole structure with one and the same substance, it being possible to construct each of the various parts with that substance which most suits its particular needs.

In order to avoid electrical concentration in the dielectric region comprised between the inside and outside coatings, A_i , A_e , it will be possible to distribute the potential gradient within the dielectric by means of conducting surfaces inserted at suitable intervals in the dielectric and in plane parallel to that of the coatings in a manner similar to a known process.

Referring now to Fig. 2, the outside coating terminals F_a , F_a , are connected to a high-frequency source HF (eventually an ordinary damped wave generator) through a tuning inductance L_f , an ammeter A and a transformer T_f . The anode P is connected to the terminal F_c of the cathode through the anode potential source E_p and a portion of the auto-transformer L_p . The other extremity of L_p is connected to the grid G and the total winding is branched across a condenser C_p .

Instead of leading in the total cathode heating current through the dielectric, it will be possible to introduce part of it conductively by means of wires sealed through the walls of the vessel and connected, on one hand to the cathode terminals and, on the other hand to either the same source HF or to an independent direct current source. In the latter case, however, care will have to be exercised in order to avoid that the high-frequency currents may not surge back into the direct current source.

In Figure 4 there is illustrated a method of supplying the cathode by the simultaneous use of a direct and of high-frequency current sources. In this figure, the high-frequency alternating current source HF is branched between the middle-point of the cathode through transformer T_f , tuning inductance L_f and an input condenser utilizing the wall of the tube as dielectric and to the two extremities of the cathode through transformer T_f , ammeter A and the input condenser in series with each cathode extremity and also utilizing the wall of the tube as dielectric.

The direct current source E_f is connected to the extremities of the cathode through an adjusting rheostat R_f and an ammeter A , the grid-cathode-anode connections being effected in a manner similar to that of Figure 2 or in accordance with any known diagram. The condenser in series with the middle point of the cathode and the inductance L_f will preferably be provided with a capacity equal to the sum of those of the condensers in series with the cathode extremities. If the latter are equal to each other,

it will be seen that the two extremities of the cathode will be equipotential from the point of view of the alternating $E. M. F.$ applied thereto and the direct current source E_f may be connected directly in shunt thereto. 70

Instead of being carried out with a single tube comprising three input condensers, the diagram of Figure 4 may be realized by means of two tubes of the type described in Figure 3 and each comprising but two input condensers. It will only be necessary to connect the tubes in series as regards the input condensers and to connect the high-frequency source between the tie linking the two tubes in series and the two extremities connected together. The direct current source should then be connected across the extremities of the two cathodes after the latter have also been conductively connected in series. It will be seen that this amounts to decomposing the single cathode of Figure 4 into two distinct cathodes having a common lead-in connection corresponding to the middle supply connection and input condenser. In the case where it would be desirable to control the electron flow by means of the variable magnetic property of the cathode itself, the latter may be made rectilinear; in other cases, it should preferably be wound in zig-zag so as to make it non-inductive. 95

While the invention has been described but in its application to the supply of current to the cathode of a thermionic tube, it must be understood that it may also be applied to any case in which it is desired to introduce large currents within hermetic insulating vessels. It may be used particularly for introducing the large heating currents used for purging the electrodes during the process of evacuation. 105

Having described my invention, I claim:

1. In combination, an envelope of dielectric material having an electric device therein, means for leading alternating current energy to said device including a condenser whereby said dielectric material is used as the dielectric of said condenser, and means for leading direct current energy to said device. 110

2. An electron discharge device comprising an envelope having a tubular body, a middle tubular branch and parallel end tubular branches, the free ends of said end branches being rounded, tubular condenser plates on the inside and outside of said end branches, said plates being rounded to fit said free ends, a filamentary cathode, an anode and control electrode in said middle branch, said filamentary cathode being connected to said inside plates, said body having three terminals located at said middle branch, said terminals having lead-in conductors connected to said cathode, anode and control electrode respectively, and containers of 115

cooling fluid in which said branches are immersed.

3. An electron discharge device comprising an envelope of dielectric material, a cathode therein, means for leading energy to said cathode including a condenser whose dielectric forms part of said envelope, an anode, between which and said cathode space current is adapted to flow, and conducting means extending to said cathode for leading the space current away from said cathode to a point external to said device.
